(57) **CLAIM**

The ornamental design for a handheld flashlight, as shown and described.

DESCRIPTION

FIG. 1 is a perspective view of a first embodiment of a handheld flashlight in accordance with the present invention; FIG. 2 is a top plan view of the first embodiment of the handheld flashlight;

FIG. 3 is a first side elevational view of the first embodiment of the handheld flashlight with a second side elevational view being a mirror image thereof;

FIG. 4 is a bottom plan view of the first embodiment of the handheld flashlight;

FIG. 5 is a front elevational view of the first embodiment of the handheld flashlight;

FIG. 6 is a rear elevational view of the first embodiment of the handheld flashlight;

FIG. 7 is a perspective view of a second embodiment of a handheld flashlight in accordance with the present invention; FIG. 8 is a top plan view of the second embodiment of the handheld flashlight;

FIG. 9 is a first side elevational view of the second embodiment of the handheld flashlight with a second side elevational view being a mirror image thereof;

FIG. 10 is a bottom plan view of the second embodiment of the handheld flashlight;

FIG. 11 is a front elevational view of the second embodiment of the handheld flashlight; and,

FIG. 12 is a rear elevational view of the second embodiment of the handheld flashlight.
